UNITED STATES PATENT OFFICE.

JONATHAN HARRIS, OF GRAND LEDGE, MICHIGAN.

SPRING CURTAIN-ROLLER.

SPECIFICATION forming part of Letters Patent No. 338,065, dated March 16, 1886.

Application filed September 30, 1885. Serial No. 178,674. (No model.)

To all whom it may concern:

Be it known that I, JONATHAN HARRIS, of Grand Ledge, in the county of Eaton and State of Michigan, have invented new and useful Improvements in Spring Curtain-Rollers; and I do hereby declare that the following is a full, clear, and exact description thereof, reference being had to the accompanying drawings, which form a part of this specification.

10 This invention relates to certain new and useful improvements in spring curtain-rollers; and the invention consists in the peculiar construction and arrangement of the parts, by means of which the curtain can be stopped at any desired point, all as more fully hereinafter set forth.

Figure 1 is a central longitudinal section through my improved roller. Fig. 2 is a perspective view of the end of the roller with the 20 cap removed, showing the arrangement of the locking mechanism. Fig. 3 is an end elevation of the spring end with cap removed.

In the accompanying drawings, which form a part of this specification, A represents the 25 part of this specification. A represents the spring end of a curtain-roller. This roller is hollow for a portion of its length, into which hollow is inserted the spindle B, around which is placed a coil-spring, C, the inner end thereof being secured in a slot, a, in the inner end of 30 the spindle, the projecting and slotted end of the spindle entering a socket, b, at the bottom of the bore.

F is the other end of the roller, similar to the part A, except that it is open at one end only.

G is an intermediate section of less diameter than the sections A F. The end g of this intermediate section is secured in the bore of the part A in any convenient manner, and is 40 provided with a socket, h, to receive the slotted end of the spindle B. The other end works loosely in the bore of the section F. The solid end of the section F is provided with a spindle or bearing, H, having a groove, i, while 45 the outer end of the spindle B is provided with a similar groove, k. By this construction I provide an extensible roller which requires no fastening means to hold the parts in their adjusted position, as the same will be held in 50 place by reason of the grooved spindles engaging with their holding-brackets.

To insure the perfect working of the curtain, and to prevent the same from sagging between the sections, I provide an adjustable sleeve, I, of same diameter as the sections A F on the 55 section G, by which it will be seen that I provide an even bearing for the curtain throughout its entire length.

D is a plug, preferably of metal, which is inserted in the bore at the open end of the 60 roller, as shown, and between this plug and the inner wall of the bore the outer end of the spring C is secured in any convenient manner, so that the spring is rigidly secured at that end. Through the center of this plug D is a 65 suitable opening, through which the outer end of the spindle B projects. The outer face of the plug is recessed, as shown, to receive upon one side the small removable rod e, which prevents the spindle B from being displaced, and 70 upon the opposite side the wall of the recess is inclined and cut away, as shown, to receive the bullet or sphere of metal d, which rests within the groove e in the periphery of the spindle. This plug, with its removable parts, 75 is secured in place by means of a cap, E, through which the end of the spindle projects, this projecting end being designed to engage with any suitable stop or fastening upon the 80 window or frame that will prevent the spindle from rolling as the curtain is operated, the opposite end of the roller being provided with any suitable pivotal point to engage with a suitable bracket.

In practice, as the curtain is pulled down 85 the roller rolls or turns upon its pivotal point, the tendency of the spring in uncoiling being to turn the roller back, and thus compress the ball between the incline and the groove in the spindle, thereby clamping such spindle firmly 90 between the ball and the short rod above described, which also lies partially within such groove. When it is desired to raise the curtain, or allow it to be rolled down the roller under the action of the spring, the curtain is 95 first pulled down slightly to disengage the ball, when, if allowed to roll quickly, the centrifugal force will throw such ball into the cut-away portion of the recess and allow the curtain to be wound up on the roller.

100 It will be observed that in this construction the spindle and spring can be removed from

the roller without marring or breaking the roller in any way, as may be required, for inserting a new spring, there being none of the parts nailed or bradded together, as in the old construction. It will also be observed that the plug D serves to retain the outer end of spring C between itself and the wall of the section A. The end F of the roller is bored out for a portion of its length to receive the diminished portion G of the end A, which may be formed as an integral part thereof; or it may be formed from a separate piece rigidly secured to the inner end of the part A. Upon this rod or part G, I slip a section of a roller, H, the diameter of which is the same as that of the sections A and F. In this construction it will be seen that both ends of the roller are adapted to be hung without cutting, and in order to fit the roller to a window the end F is removed and the end of the rod G cut off sufficiently, so that when the parts are again put together the roller will be of the desired length to fit the window upon which it is to be used.

I am aware of the English Patent No. 731 of 1856, which shows a telescopic roller but no sleeve to prevent the sagging of the curtain

between the end sections when the roller is extended, and such construction I disclaim; neither do I claim the construction shown in the Patent No. 302,379, July 22, 1884.

30

What I claim as my invention is—

1. The combination of the end sections, A F, of like diameter, of the intermediate section, G, of less diameter than said sections A F, and the sleeve I, of the same diameter as 35 the end sections, substantially as and for the purpose specified.

2. In a spring curtain-roller, the combination, with the roller, of a plug inserted in one end thereof, the spindle B, passing through an opening in said plug and having groove e, said plug being recessed to receive upon one side the pin c, and its opposite side inclined, as shown, and the ball d, resting in the groove in the spindle, all constructed, arranged, and operating substantially as and for the purpose specified.

JONATHAN HARRIS.
